(57) **CLAIM**

The ornamental design for a lid for a beverage container, as shown and described.

DESCRIPTION

FIG. 1 is a front, top perspective view of a lid for a beverage container showing our new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines and unshaded surfaces within them on the bottom of the article and the broken lines forming letters on the handle depict portions of the lid for a beverage container that from no part of the claimed design.

1 Claim, 8 Drawing Sheets
